UNITED STATES PATENT OFFICE.

SWAN SMITH, OF WHITE BEAR, MINNESOTA, ASSIGNOR OF ONE-HALF TO WEST PUBLISHING COMPANY, OF ST. PAUL, MINNESOTA, A CORPORATION OF MINNESOTA.

BOOK END SECTION.

Application filed May 16, 1927. Serial No. 191,936.

My invention relates to improvements in methods of forming book end-sections.

The conventional book end-section including a fabric hinge-strip, in practically all instances, is made up by hand in the following manner: A number of stacked sheets, combed down to expose successive marginal areas thereof, are pasted along said exposed areas. The uppermost sheet of the combed pack is slid back a short distance on the next sheet and a fabric strip 10 (Fig. 8 of the drawing) disposed on said two sheets with one longitudinal marginal portion of said strip lying upon the pasted margin 11 of one sheet 12 and the opposite marginal portion of said strip lying upon the pasted margin 13 of the other sheet 14. The fabric strip is then sealed to said sheets, the result being that an assembly of sheets and strip is provided, one sheet being bound by a fabric flap and secured to the other sheet through said flap. The sheet 12 having the fabric flap 10 is known as the end-sheet, the other sheet 14 being known as the fly-leaf. Said assembly of sheets and hinge-strip is gathered with a printed terminal section 15 (Fig. 2) that has been pasted along the back margin of the inner sheet thereof, the fly-leaf of the assembly being laid next to the outer sheet of the printed-section. The marginal portion of the assembly is turned over the back edge of the printed section, the margin of the fly-leaf being brought against the pasted margin of said printed-section, the lines of fold in the assembly occurring in the fly-leaf and in the flap or hinge-strip, which superimposes said fly-leaf. Thus, an end-section is completed by hand and ready for hand binding in a book, after which process, the end-sheet is pasted to the adjacent book cover.

In attempting to obtain quantity production in binderies it has been found that one of the chief impediments resided in the customary slow method of manually forming end-sections, as above explained, the result being that an urgent need developed for a practical method of forming end-sections by machinery.

Experiments with machinery for supplanting hand labor has seemed to require changes of one kind or another in the conventional form of end-sections, none of which changes appear to meet with the approval of experienced binders. The problem, therefore, of evolving a method for making conventional book end-sections, which method may be car-

ried out practically in mechanism for forming such end-sections, has been presented and is met in my present invention.

An object of my invention is to provide a method for forming conventional book end-sections, wherein a single elongated sheet is folded end-to-end to provide an end-sheet and a fly-leaf, whereby with such folded sheet simple mechanisms may serve to handle the same and maintain the requisite relative disposition of the embodied end-sheet and fly-leaf and, whereby the appropriate application, mechanically, of a hinge-strip to said members is simplified.

The foregoing and other objects of the invention will more fully appear in the following specification and claim.

In the accompanying drawing, Fig. 1 is a fragmentary view of a book end-section formed by my improved method of constructing such end-sections; Fig. 2 is a fragmentary view of a conventional printed terminal section; Fig. 3 is a fragmentary view of an elongated sheet employed in my improved method; Fig. 4 is a fragmentary view of such sheet illustrating a hinge strip as bound thereto in the process; Fig. 5 is a view of such sheet illustrating the same in the act of being folded upon itself; Fig. 6 is a view, progressed beyond that of Fig. 5, showing the completed fly-leaf, end-sheet and hinge strip assembly; Fig. 7 is a further progressed view showing such assembly gathered with a printed terminal-section and being turned at the hinged margin thereof over the back of said terminal-section, and Fig. 8 is a view showing the separate fly-leaf and end-sheet separately pasted and arranged in their relative positions under the old method of providing such independent members with a hinge-strip.

Similar parts in the several views of the drawings, bear similar reference characters to which I have hereinbefore made reference and to which I shall refer in the following specification.

In my improved method of forming the conventional book end-sections, which comprises a printed terminal-section, a fly-leaf and a fabric hinged end-sheet for attachment to a book cover, I arrange for the provision of the fly-leaf and end-sheet in a single elongated sheet A which may be folded from end-to-end along a transverse line near the center of such sheet. By thus employing a sheet of this description to provide two members of

the ultimate end-section B (Fig. 1), viz; the fly-leaf 14^a and end-sheet 12^a, I allow for the marked simplification of expedients required in a machine for automatically forming book end-sections.

The method preferably provides for the pasting of opposed end margins of the elongated sheet A on opposite faces thereof as at 11^a and 13^a, then marginally seating a 10^a fabric hinge-strip 10^a to one of the pasted margins 11^a, then folding the elongated sheet end-wise and slightly off-center to bring the free margin of the hinge-strip onto the other pasted margin 13^a of said elongated sheet 15 and thereby form the fly-leaf 14^a and also the companion end-sheet 12^a therefor in the desired composite form which consists, in the main, of the outer fold of the elongated sheet and includes the back bordering fabric strip 20 10^a having marginal connection with the back margin of said fly-leaf 14^a. In pasting the single elongated sheet, rather than two separate smaller sheets as at 12 and 14, Fig. 8, the operation by means of mechanisms is 25 simplified by reason of the fact that it is easier to provide a structure for handling and operating upon one relatively large sheet than it is to provide a structure for handling and operating upon two separate and relatively small sheets. Then too, the problem 30 of mechanically holding the fly-leaf and end-sheet in their relative positions during the mounting of the hinge-strip is more simple, when such members are attached to one another, as they are in the folded sheet, than when such members comprise separate sheets 35 detached from one another. Further mechanical simplifications are possible under the present method wherein the fabric hinge-strip is first secured at one margin to a 40 margin of an elongated sheet (Fig. 4) and then, after the folding of the sheet (Fig. 5), is secured at its other margin to another margin of said sheet (Fig. 6). This will become 45 apparent when it is noted that buckling of the hinge-strip is largely avoided in severally sealing its margins to its companion members and that the handling of said hinge-strip in such application thereof to said 50 members is much more simple, mechanically, than it is to apply the hinge-strip to spaced pasted areas in one operation.

Having formed the fly-leaf, end-sheet and hinge-strip assembly (Fig. 6) by folding a long sheet to provide the fly-leaf and end-sheet and by affixing the hinge-strip, partially before the folding of said sheet and partially thereafter, as above explained, said assembly is gathered with a terminal printed section (Fig. 7), the fly-leaf being disposed next to the outer sheet of said printed section with the back marginal portion of the assembly overreaching the back edge of the printed section. This over-reaching marginal portion of said assembly is then turned about said back edge of said printed section to lap upon the back margin of the inner sheet of said section. This back margin having been treated with paste as at 15^a, Fig. 7, prior to the gathering of the printed section with said assembly results in a bonding seal between the turned over portion of the fly-leaf and said inner sheet of the printed section, whereupon the formation of the end-section is complete.

The present method of forming book end-sections is particularly advantageous in that it may be carried out in practical machines simplified to such extent as to be comparatively inexpensive in first cost and in operation as well.

Changes in the method as herein specifically described may be made within the scope of what is claimed without departing from the spirit of my invention.

Having described my invention, what I claim as new and desire to protect by Letters Patent is:

A book end-section comprising a terminal printed section and an end-sheet and hinge-strip assembly, said assembly including an elongated sheet folded upon itself on a transverse line off center of the sheet to bring the ends thereof in spaced relation and further including a hinge-strip marginally secured to the free ends of said folded sheet, said assembly being marginally turned over the back edge of the printed section on a line of fold extending longitudinally of the hinge strip, the back turned portion of said assembly being secured to the printed section.

In testimony whereof, I have signed my name to this specification.

SWAN SMITH.
